US0D1005267S

(12) **United States Design Patent** (10) **Patent No.:** **US D1,005,267 S**
(45) **Date of Patent:** **** Nov. 21, 2023**

(54) **EARPHONES**

(71) Applicant: **Dongguan Yongfang Electronics Technology Co., Ltd**, Dongguan (CN)

(72) Inventor: **Dan He**, Dongguan (CN)

(**) Term: **15 Years**

(21) Appl. No.: **29/869,565**

(22) Filed: **Jan. 4, 2023**

(30) **Foreign Application Priority Data**

Sep. 24, 2022 (CN) 202230634018.2

(51) **LOC (14) Cl.** **14-01**

(52) **U.S. Cl.**

USPC **D14/223**

(57) **CLAIM**

The ornamental design for earphones, is as shown and described.

DESCRIPTION

FIG. 1 is a perspective view of earphones showing my new design;

FIG. 2 is the other perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 7 Drawing Sheets
